COMBINATION CLOTHES HANGER AND CABINET

Belle A. Kandarian, Fresno, Calif.

Application June 23, 1952, Serial No. 20,313

Term of patent 14 years

(Cl. D80—8)

To all whom it may concern:

Be it known that I, Belle A. Kandarian, a citizen of the United States, residing at 920 R Street, Fresno, county of Fresno, and State of California, have invented a new, original, and ornamental Design for a Combination Clothes Hanger and Cabinet, of which the following is a specification, reference being had to the accompanying drawing, forming a part hereof.

Fig. 1 is a plan view of a combination clothes hanger and cabinet, showing my new design.

Fig. 2 is a side elevation of the combination clothes hanger and cabinet shown in Fig. 1.

Fig. 3 is a perspective view taken from an end of the combination clothes hanger and cabinet and the side thereof opposite to that shown in Fig. 2.

Fig. 4 is a perspective view of the combination clothes hanger and cabinet showing the end and side thereof opposite to the end and side shown in Fig. 3.

I claim:

The ornamental design for a combination clothes hanger and cabinet, as shown.

BELLE A. KANDARIAN.
